CLAIM

The ornamental design for a swivel table design, as shown and described herein.

DESCRIPTION

FIG. 1 is a top, front, left side perspective view of a swivel table design according to the present invention;

FIG. 2 is a front elevation view thereof.

FIG. 3 is a back elevation view thereof.

FIG. 4 is a left side elevation view thereof.

FIG. 5 is a top plan view thereof.

FIG. 6 is a bottom plan view thereof.

FIG. 7 is a right side elevation view thereof.

FIG. 8 is a top, front, left side perspective view of the swivel table design of FIG. 1 with the movable portions in a second position.

FIG. 9 is a top, front, left side perspective view of the swivel table design of FIG. 1 with the movable portions in a third position.

FIG. 10 is a top, front, left side perspective view of the swivel table design of FIG. 1 with the movable portions in a fourth position.

FIG. 11 is a top, front, left side perspective view of the swivel table design of FIG. 1 with the movable portions in a fifth position.

FIG. 12 is a top, front, left side perspective view of the swivel table design of FIG. 1 with the movable portions in a sixth position; and,

FIG. 13 is a top, front, left side perspective view of the swivel table design of FIG. 1 with the movable portions in a seventh position.

The broken lines shown in FIGS. 1-4 and 6-13 are included for the purpose of illustrating environmental structure and form no part of the claimed design.

1 Claim, 11 Drawing Sheets
